UNITED STATES PATENT OFFICE.

ALFRED L. PARMELEE, OF LAMBERTVILLE, MICHIGAN, ASSIGNOR OF ONE-HALF TO
SEYMOUR B. GOODKIND, OF TOLEDO, OHIO.

PRINTING-PRESS.

1,238,325.

Specification of Letters Patent. Patented Aug. 28, 1917.

Application filed April 27, 1916. Serial No. 93,891.

To all whom it may concern:

Be it known that I, ALFRED L. PARMELEE, a citizen of the United States of America, residing at Lambertville, Monroe county, 5 Michigan, have invented new and useful Printing-Presses, of which the following is a specification.

This invention relates to presses for the multiplication of impressions or copy.

10 This invention has utility when incorporated in a roll printing press.

Referring to the drawings:

Figure 1 is a perspective view of an embodiment of the invention in a rotary printing press;

15 Fig. 2 is a showing of the inking and impression trains in operative position;

Fig. 3 is also a view of the inking and impression trains but with the inking and 20 impression rolls thrown off, the throw-off mechanism being shown;

Fig. 4 is an end elevation of the roll actuating train;

25 Fig. 5 is a fragmentary view of the inking train features;

Fig. 6 is a fragmentary perspective view of the cutting mechanism; and

30 Fig. 7 is a fragmentary detail view on an enlarged scale of the feed driving connections.

The printing press embodies the cylindrical rotary ink fountain 1 loosely mounted in the forks 2 by the shaft 3, said roller 1 resting upon the distributing roller 4 coacting with the supplemental ink distributing 35 rolls 5. The rolls 5 have their shafts 6 in the inclined ways 7 allowing these rolls to fall against the side of the roller 4 which has its shaft 8 mounted in the lower part of 40 the forks 2.

Disposed below the roll 4 is the live roll 9 of the inking train mounted on the shaft 10. This roll 9 coacts with the roll 4 and may coact with the rolls 11 on the shafts 12 in 45 conducting the distributed ink from the inking train to the copy 13 on the copy carrying roll 14 mounted on the shaft 15 having eccentric bearings. This copy carrying roll may transfer its copy to the soft blanket 50 or offset 16 on the first offset roll 17 mounted on the shaft 18 which may in turn transfer from its blanket an impression to the blanket 19 on the second roll 20 mounted on the shaft 21 from which continuous copy im- 55 pressions may be transferred to material

passing between this second offset roll 20 and the impression roll 22 mounted on the shaft 23 in the eccentric bearing 24 carried by the main printing press frame 25. This frame 25 has the lower portion thereof 60 mount the motor 26 driving from the worm 27 and the worm wheel 28, the shaft 29 coacting through the spiral pinion 30 and spiral gear 31 to drive the shaft 18 of the first offset roll.

This shaft 18 at its opposite end has the herring-bone gear 32 in mesh with the herring-bone gear 33 on the shaft 15 which, through the herring-bone pinion 34 on the stub shaft 35 drives the herring-bone gear 36 on the shaft 10. This gear 36 has the wrist pin 37 with universal joint 38 connected to link 39 having universal joint 40 connected to the bell crank lever arm 41, mounted on the fulcrum 42, and its upper 75 arm 43 connected by the universal joint 44 to reciprocate the shaft 3.

Accordingly the operation of the motor 26 rotates the shaft 29 and first offset roll 17. Copy roll 14 is a live or positively driven 80 roll as is also the inking train roll 9. The ink fountain roll 1 is reciprocated across the distributing roll 4 and the rotation of the roll 9 is transmitted to these follower rolls 5, 4 and 1, as also to the follower rolls 11 85 for effective distribution of the impression substance to the copy 13 on the copy roll 14. The herring-bone gearing precludes any lost motion in the mechanism notwithstanding the throwing of the parts into throw-off position, and this is also true of the spiral gear drive. The same diameter for copy 13 and roll 9 simplifies the throw adjustment.

In mesh with the herring-bone gear 32 is the herring-bone gear 45 on the shaft 21 of 95 the second offset roll which is in mesh with the herring-bone gear 46 on the shaft 23 of the impression roll, thereby making a positively driven impression or copy transfer train. The treadle 47 mounted on the fulcrum shaft 48 in the frame 25 is normally held upward by the spring 49 from the frame cross bar 50. When this treadle 47 is actuated against the resistance of the spring 49 and thrown into the latch 51, 100 this tread lever acts, through the link 52 and arm 53 to rock the shaft 54 in the frame 25. Connected to this rock shaft 54 is the pair of arms 55 from which extend upward the links 56 connected by arms 57 to the ec- 110

centric bearings 24 of the impression roll 22. Further extension links 58 are connected by the arms 60 to the eccentric bearings 61 for the shaft 15 of the copy carrying roll 14. These links 58 have link extensions 62 connected to the angle lever 63 fixedly fulcrumed intermediate the rolls 11 and connected thereto by the arms 64. The arms of lever 63 have adjustable connections to vary the throw. This movement upward of the treadle 47 rocks this angle lever 63 to throw its central portion out of vertical position and accordingly throw the rollers 11 outwardly in the guides 65 medially between the shafts 10, 15. This throws this lower pair of rollers of the inking train free of the copy 13, while the upward travel of the links 56, 58 acting through the arms 57, 60, has so thrown the eccentric bearings 24, 61, that the copy 13 is spaced to clear the first offset roll 17 while the impression roll 22 is thrown away from the second offset roll 20.

The herring-bone gearing maintains the operating registry between the train rollers notwithstanding the throw off and the movement of the inking rollers of the impression train out of contacting relation. Accordingly, when the treadle is released, the former registry is had at once.

The material to be supplied, as sheets of paper for copy, may be passed from the table 65 and the feeding occur automatically by the driving mechanism from the shaft 21 of the second offset roll which has thereon the mutilated gear 66 to drive the loose pinion 67 on the shaft 68. This pinion 67 has the guide or holding recess 69 to rest against the plate 70 adjacent the mutilated gear 66 in the range of the toothless portion of said gear 66, thereby holding the pinion 67 from rotation except at the toothed portion of the gear 66. This pinion 67 is in mesh with the pinion 71 fast on the shaft 45 72 carrying the stock feeding cams 73 and the additional cam 74, the latter acting to lift the bar 75 against the resistance of spring 76 and thereby, through the rock-shaft 77 hold the fingers 78 in up position 50 to interfere with the feed of paper stock. In the rotation of this shaft 72 when the cams 73 are in stock feeding position the cam 74 is in position to allow the fingers 78 to be dropped by the spring 76. The feeding of the paper is normally guided by the guide fingers 79.

The travel of the stock from the table

65 as to the cam 73 is facilitated by the pinion 79 driving the shaft 80 acting as a live roll. This shaft 80 is mounted in an oval bearing 81 and may have its clearance relation as to the cam 73 adjusted by the thumb screw 82, forcing the pinion 79, 71, into more or less depth of root register.

As the stock passes between the second offset roll 20 and the impression roll 22, it may be severed into the desired length sheets by the cutting edge or knife 83 anchored by screws 84 into the slot in the impression roll 22, coacting with an opposing metal seat 85 in the second offset roll 20.

This printing press is of simple compact construction for a wide range of use in turning out superior work even on rough or low grade stock. The offset feature permits the delicacy of reproduction from copy requiring accuracy and minute showings even on the rougher stocks. Further, this reproduction may occur with the usual copy which at the first impression gives the right or printing impression. This first impression is reversed by the second offset to give the final printing impression. Regular copy, say set up type, as well as cuts may be used as a projecting form copy on this apparatus and with superior results and a high degree of simplicity for job work.

What is claimed and it is desired to secure by Letters Patent is:

A printing press embodying a frame providing a pair of opposing members, a bank of rolls mounted in said members including a first offset roll, driving means for said offset roll, a copy roll on one side of said offset roll, a second offset roll on the opposite side of the first offset roll from the copy roll, an impression roll beyond the second offset roll, gears on said rolls for transmitting driving action from the first offset roll, an idler gear beyond the copy roll driven by the copy roll gear, an inking roll provided with a gear in mesh with said idler gear, an ink distributing roll provided with longitudinal actuating connection with said idler driven gear whereby said ink distributing roll is reciprocated as to the inking roll, said bank of rolls having their axes lying approximately in a common plane, said inking roll and copy roll being of similar diameter, and an ink applying follower roll actuated by the inking roll and coacting with the copy roll.

In witness whereof I affix my signature.

ALFRED L. PARMELEE.
